UNITED STATES PATENT OFFICE.

BRYCE W. McCLYMONT, OF DETROIT, MICHIGAN, ASSIGNOR TO PENERBTHY INJECTOR COMPANY, OF DETROIT, MICHIGAN, A CORPORATION OF MICHIGAN.

STEAM-HEATING APPARATUS.

1,378,252.

Specification of Letters Patent. Patented May 17, 1921.

Application filed November 27, 1918. Serial No. 264,410.

To all whom it may concern:

Be it known that I, BRYCE W. McCLYMONT, a citizen of the United States, residing at Detroit, in the county of Wayne and State of Michigan, have invented certain new and useful Improvements in Steam-Heating Apparatus, of which the following is a specification.

My invention relates to heating apparatus in which a hydraulic ejector operating as an exhausting device is used to produce a vacuum in the return passages of a heating system, and may be regarded as an addition to and improvement upon a hydraulic vacuum generator or pump described in McClymont Patent No. 1,265,928 issued on May 14, 1918. The object of my invention is to render the exhausting pump described in said patent more efficient and useful by the provision of a combined check valve and float valve device affording safeguards against certain irregularities in its operation which are liable to occur under certain conditions. With this purpose and incidental objects and advantages in view I have designed and invented the novel structure hereinafter particularly described, the essential elements of my invention being pointed out in the appended claims, it being understood, however, that my invention is susceptible of modification in the form and specific construction of its parts without departing from the spirit of my invention or the scope of the claims.

In the drawings, Figure 1 is a diagrammatic view of a heating system to which my invention is applied; and Fig. 2 is a central longitudinal section of a hydraulic vacuum generator and a combined check valve and float valve embodying my invention associated therewith.

The same reference characters indicate the same parts in both figures of the drawing.

The ordinary boiler and steam supply pipes and return pipes and the ejector exhausting device to which my present invention is applied, may be constructed in accordance with the "single pipe" system shown in McClymont Patent No. 1,265,928 above mentioned, or the "double pipe" system herein illustrated. Inasmuch as the latter arrangement is well known to those skilled in the art, a brief description thereof will suffice for present purposes. As

shown in Fig. 1 of the drawings, the boiler communicates with steam pipes 2 leading to the radiators 3, and the water of condensation is conducted back to the lower part of the boiler through the return piping 4. Thermostatic valves 5, constructed to permit the passage of cold air and water vapor which may accumulate during periods when the system is idle and the radiator is out of use and constructed to be closed by the action of the hot steam, are arranged to govern communication between the radiators and the return system of connected pipes 4. The return piping is provided with a vertical air-pipe 7 forming an air trap which is connected at some convenient point above the water level of the boiler to the vacuum generating device to be next described.

As shown, the vacuum generating device comprises an ejector casing 8 having valve-governed communication with a supply of water under pressure, as the service pipe 9 of a water system, and a discharge outlet 9^a leading to a sewer or other conduit for carrying the waste water away. The ejector members 10 and 11 are arranged to produce a vacuum within a chamber in the casing which communicates with the closed side of a spring-pressed diaphragm 12 mounted in a diaphragm casing 13. The admission valve 14 of the device is normally closed, but by suitable connections 15 arranged for manual operation and co-operating with an actuating lever 16 it may be opened to permit a flow of water through the ejector, thus creating a vacuum within the vacuum chamber and communicating passages. The lever 16 is connected with the diaphragm 12 by a link 17 having a lost motion or one-way engagement with the lever which permits the admission valve to be opened without affecting the diaphragm when the latter is in uppermost position, but which causes such valve to be shifted from open to closed position by downward movement of the diaphragm from such uppermost position under the influence of preponderating atmospheric pressure on its outer side.

According to my present invention, the vacuum chamber of the vacuum generating device communicates with the air pipe 7 of the return pipes of the apparatus through a combined check and float valve which will

now be described. The casing 18 of the valve is formed with a depending screw-threaded nipple 19 by means of which it may be connected to the air pipe 7 of the system, this nipple being formed with a spider 20 which provides a bearing for the hollow stem 21 of the float 22. The upper member or cap 23 of the casing is formed with an externally threaded nipple 24 by means of which it is secured to a threaded connection 25 formed on the lower wall of the vacuum chamber of the ejector. This nipple is bored out to form a ball chamber for the reception of a ball check-valve 26 coöperating with a seat at the bottom of the chamber, a ball-retainer 27 consisting of a diametrical cross-pin being provided to prevent the ball from getting out of the chamber. The cap 23 is provided also with a depending tubular guide block 28 arranged to slidably receive the upper end of the valve stem 21. The coned head 29 which forms the valve member proper of the float valve is equipped with a vertical pin 30 which, as the valve approaches closed position contacts the ball check valve and opens it. As shown the block 28 is formed with relief orifices 31 adjacent its base, and the hollow valve stem is provided with a vent opening 32 near its top.

The function of the check valve just described is to maintain the vacuum created by the ejector throughout the return passages of the system under normal conditions, and the function of the float valve is to destroy said vacuum and prevent a flow of the water of condensation through the ejector under certain conditions which are liable to occur. If the boiler pressure and the vacuum produced by the action of the ejector should be such as to cause an unbalanced water level in the boiler and the return pipe, and sufficient to overcome the height of the ejector device above the balanced water level, the result would be (assuming the vacuum chamber to be directly connected with the air-pipe 7, without the float valve structure herein described) that the water of condensation would pass through the pump and be ejected, or siphoned out, into the sewer. Under such pressure conditions, however, with the arrangement herein described, the float valve 29 closes and checks the water before it reaches the ejector, and the water of condensation will return to the boiler as soon as the pressure therein becomes such that the pressure head of the water of condensation in the return pipe exceeds the boiler pressure. When the water of condensation raises the float to close the float valve, the pin 30 opens the check valve 26 and destroys any vacuum that would have a tendency to pocket the water in the body of the valve. This tendency is further guarded against by making the stem of the

float valve hollow and venting the interior above the float. As the water of condensation recedes into the boiler, the vent through the stem destroys any vacuum in the tube and therebelow and permits the water to 70 drain away instantly.

In such installations as employ the "single pipe" system, the steam pipes are connected to the lower parts of the radiators so that any water of condensation which may 75 form will flow toward the boiler by gravity through the steam pipes. In such case small return pipes for the return or venting of air only and connected to the upper part of the radiators are provided, this being the arrangement shown in McClymont Patent No. 1,265,928, before mentioned. This system of connected air pipes may be provided with a drain connection to the lower part of the boiler for returning to it whatever water of 80 condensation may find its way into the air pipes, and the return air pipe of the system is connected to the float and check valve of the hydraulic pump in the same manner as the return pipe of the double pipe system 85 hereinbefore described.

I claim:

1. In a heating system, including a boiler and steam supply pipes and return passages including an air pipe and a branch pipe 95 communicating with the boiler below its water level, the combination of a vacuum pump having an exhausting chamber and ejector members arranged to induce a vacuum in such chamber, and a valve device 100 above the water level of the boiler having a float chamber provided with upper and lower openings, said chamber communicating through said lower opening with said air pipe, and said valve device having a 105 float and connected valve in said float chamber arranged to prevent the passage of water through said upper opening into said exhausting chamber.

2. In a heating system, including a boiler and steam supply pipes and return passages including an air pipe and a branch pipe communicating with the boiler below its water level, the combination of a vacuum pump having an exhausting chamber and ejector members arranged to induce a vacuum in such chamber, and a valve device 115 above the water level of the boiler having a float chamber provided with upper and lower openings, said chamber communicating through said lower opening with said air pipe, and said valve device having a float 120 and connected valve in said float chamber arranged to prevent the passage of water through said upper opening into said exhausting chamber, and a check valve arranged to prevent passage of air from said exhausting chamber into said float chamber.

3. In a heating system, including a boiler and steam supply pipes and return passages 125

including an air pipe and a branch pipe communicating with the boiler below its water level, the combination of a vacuum pump having an exhausting chamber and 5 ejector members arranged to induce a vacuum in such chamber, and a valve device above the water level of the boiler having a float chamber provided with upper and lower openings, said chamber communicat- 10 ing through said lower opening with said air pipe and said valve device having a float and connected valve in said float chamber arranged to prevent the passage of water through said upper opening into said ex- 15 hausting chamber, and a check valve ar- ranged to prevent passage of air from said exhausting chamber into said float chamber, said float valve being arranged to automatically open said check valve as such float 20 valve closes.

4. In a heating system, including a boiler and steam supply pipes and return passages including an air pipe and a branch pipe communicating with the boiler below its 25 water level, the combination of a vacuum pump having an exhausting chamber and ejector members arranged to induce a vacuum in such chamber, and a valve device above the water level of the boiler having 30 a float chamber provided with upper and lower openings, said chamber communicat- ing through said lower opening with said air pipe and said valve device having a float and connected valve in said float chamber 35 arranged to prevent the passage of water through said upper opening into said ex- hausting chamber, and a check valve ar- ranged to prevent passage of air from said exhausting chamber into said float chamber, 40 said float valve being equipped with a pin adapted to contact said check valve and open the latter as such float valve closes.

5. In a heating system, including a boiler and steam supply pipes and return passages 45 including an air pipe and a branch pipe communicating with the boiler below its

water level, the combination of a vacuum pump having an exhausting chamber and ejector members arranged to induce a vacuum in such chamber, and a valve device 50 above the water level of the boiler having a float chamber provided with upper and lower openings, said chamber communicat- ing through said lower opening with said air pipe and said valve device having a float 55 and a connected vertical hollow valve stem and valve in said float chamber arranged to prevent the passage of water through said upper opening into said exhausting cham- ber, said hollow stem having a vent opening 60 adjacent its upper end.

6. A heating system according to claim 2 in which said valve device includes a lower casing member forming the float chamber and a cap member having a tubular upward 65 connection chambered to form a check valve chamber and having a depending tubular guide block adapted to slidingly receive the upper end of said valve stem.

7. A heating system according to claim 2 70 in which said valve device includes a lower casing member forming the float chamber and a cap member having a tubular upward connection chambered to form a check valve 75 chamber and having a depending tubular guide block adapted to slidingly receive the upper end of said valve stem, said guide block being orificed near its base.

8. A heating system according to claim 2 80 in which said valve device includes a lower casing member forming a float chamber and a cap member having a tubular upward connection chambered to form a ball chamber 85 and having a depending tubular guide block to slidingly receive the upper end of said valve stem, and in which said check valve is a ball arranged in said ball chamber and the top of said valve stem is provided with a valve and such valve is equipped with a pin arranged to coöperate with said ball check 90 valve.

BRYCE W. McCLYMONT.
